United States Patent Office

Des. 204,765

Patented May 17, 1966

204,765

BILLY CLUB

William R. Black, 1311 Liberty St., La Crosse, Wis.

Filed May 19, 1965, Ser. No. 85,362

Term of patent 14 years

(Cl. D30—1)

I claim:

The ornamental design for a billy club, as shown.
